UNITED STATES PATENT OFFICE.

MARTIN HOKANSON, OF DULUTH, MINNESOTA.

APPARATUS FOR CLASSIFYING GRANULAR MATERIAL.

Application filed March 4, 1922. Serial No. 541,168.

To all whom it may concern:

Be it known that I, MARTIN HOKANSON, a citizen of the United States, and a resident of Duluth, State of Minnesota, have invented a new and useful Improvement in Apparatus for Classifying Granular Material, of which the following is a specification.

This invention relates to an apparatus for classifying granular material and has for an object the provision of a device that will readily and efficiently effect a separation of the particles comprising a granular material into grades or classes according to their respective sizes.

Although the device is adapted for general use wherever it is desirable to effect a separation or classification according to the size of the particles comprising the material, it is particularly adapted and intended for use in connection with the separation of the valuable parts of ore from gangue.

It is a special object to provide a device for effecting the desired purpose without the use of screens or shaking tables, in which the separation is produced by utilizing the greater rolling action of the larger particles, in which the material is operated upon while in the form of a thin sheet whereby the induced rolling action will effect a sharp and clean separation of the particles, in which the path of the rolling particles will be of considerable length without necessitating parts of cumbersome proportions, in which the rolling action is a positively induced one and which can be easily varied to suit varying conditions, and in which means are employed to enhance the effectiveness of the rolling action of the larger particles by preventing or hindering the rolling action of the smaller particles of the material.

It is also an object to provide a device possessing a large capacity of production without detracting from its effective operation to produce a sharp separation, which is of simple construction, easy to operate and repair, and which can be economically manufactured.

These and other objects of the invention will more readily appear when taken in connection with the following description and the appended claims.

In the accompanying drawings, Fig. 1 is a diagrammatic view with parts in section illustrating one embodiment of the invention; Fig. 2 a fragmentary view of a modi-

fied form; and Fig. 3 a transverse sector taken on line III—III of Fig. 2.

The embodiment of the invention shown in Fig. 1 comprises a supporting framework consisting of the upright members 1, only two of which are shown, and transverse members 2, said framework resting upon a suitable foundation 3.

Suspended in any desirable way between the upright members 1, and concentrically arranged, are a plurality of annular funnel shaped collecting compartments 4, 5 and 6 having inclined bottoms and equipped with the discharge chutes 7, 8 and 9 respectively. The several annular compartments are suitably connected and spaced apart at intervals by means of vertical sheet separators of well known construction, those adjacent the top portions being indicated at 10 and those nearer the bottom at 11, the assembled compartments being suspended as a unit by attaching the exterior wall of the outer compartment 6 to the upright 1 at 12. These compartments may be constructed of any suitable material, preferably of metal, and the space between the inner compartment 4 forms a chamber which is closed by a top 13 having at its center a bearing 14. A spider 15 mounted in this chamber also carries a bearing 16 aligned with bearing 14 in which a shaft 17 is journaled, said shaft extending through a tubular prolongation 18 projecting downwardly from the chamber.

The tubular extension 18 serves as an inner wall for the lower end of compartment 4 and also as a housing for the shaft 17. Shaft 17 is centered and supported by a foot bearing 19, and attached thereto adjacent the foot bearing is a driving pulley 20 adapted to be driven from any suitable source of power by means of the belt 21.

Attached to the upper end of shaft 17 and disposed immediately above the top 13 is a circular distributing disk or table 22. The upper surface of the disk is preferably covered by a sheet 23 of some material which offers a high frictional resistance to sliding motion of the particles deposited thereon, rubber and canvas being particularly adapted for such purpose. In actual practice if the covering extends over the entire disk feeding of the material upon the conical central portion will rapidly wear away the same. To avoid this disadvantage, the body of the disk may be made of a material having high wear resisting qualities, leaving the

conical center exposed with the covering extending within a short distance therefrom to the peripheral edge of the disk, or a two part covering may be employed having the 5 central portion of a material possessing the necessary wear-resisting qualities. The upper surface of the disk or table 23 is somewhat higher at its central point in order to distribute the material evenly from which it 10 preferably slopes downwardly along a curved path to its intermediate portion and thence curves upwardly to its periphery, the edge of which is rounded as shown. This rounded edge is of special utility when the 15 material operated upon is mixed with water, in a manner to be presently described, due to the greater surface tension between the water and the table than between the water and the particles of material carried 20 thereby.

The material to be treated is fed upon the table 22 at its center 24 from an agitating hopper 25 suspended at 26 in the transverse members 2, is deposited upon the table at 25 a low velocity, and due to the conical shape of the center of the table it will immediately spread out in the form of a thin sheet. This discharge mouth 27 of the hopper is disposed directly over the center of the table 30 and at a very short distance therefrom, and is provided with a regulating valve 28 towards which the funnel shaped bottom of the hopper gradually slopes.

The feed hopper may be filled in any desired manner. The embodiments illustrated are particularly intended for use in connection with mixtures of ores and gangue which are introduced through a conduit 29 controlled by gate valve 30, while the supply 35 of water with which it is mixed is introduced by means of pipe 31 provided with a valve 32. Mounted within the hopper is an agitator consisting of shaft 33, carrying 40 wings or blades 33', journaled in bearings 34 and 35 supported by spiders 36 and 37, respectively. Attached to the upper extremity of shaft 33 is a bevel pinion 37' meshing with a second bevel pinion 38 fixed to a shaft 39 driven from any suitable 45 source of power. By such means the ore and water can be thoroughly mixed to separate the particles from each other and to maintain the mixture in a uniform condition.

In use, if dry material is operated upon, the granular material is deposited from the hopper at a low velocity, and in such 50 quantity as to insure its being spread out in the form of a thin sheet upon the rotating table or disk 22 by the time it reaches the lowest depression on the table. Due to the differences in sliding and rolling friction between the particles and the supporting surface of the table, and to the fact that the 55 larger particles more easily acquire a roll-

ing motion under the influence of the several impelling forces, a rolling action is immediately induced in the larger particles, the lineal velocity of which gradually increases as said particles approach the peripheral 70 edge of the table, the final velocities obtained varying in accordance with their relative sizes. The smaller particles consequently do not tend to roll easily relatively to the larger particles and under practical 75 operating conditions, do not attain but a small velocity relative to the larger particles as a result of their rolling motion.

Due to the above described action it is obvious that by the time the several particles 80 reach the peripheral edge of the table, the largest particles have assumed a high velocity away from said edge, and the smallest particles a comparatively low velocity, while the particles of intermediate size acquire a velocity therebetween. The largest particles are therefore projected the greatest distance from the table and are caught in the outer annular compartment 6, the smallest particles fall into the inner compartment 4, and those of intermediate size are collected by the middle compartment 5.

In the embodiments illustrated only three compartments are used which separate the particles into but three grades. The same 95 principle of separation applies, however, regardless of the number of collecting compartments employed, so that by varying the number of said compartments the number of 100 grades into which the particles are separated 100 may be varied at will.

Although a similar separation is effected by using a table of the form shown without a covering of material, such as rubber or canvas, the difference between the rolling motion induced in the large and small particles with the consequent difference in their final velocities is greatly enhanced by its use.

The operation so far described has had 110 reference especially to the treatment of materials in a dry condition in which the several particles do not cling tightly together. It is impossible to effect a clean separation of certain materials due to their 115 normally moist condition or because of the presence of substances which act as binders to cause the particles to stick to each other. If the materials are thoroughly 120 mixed with water so as to free the particles from each other and this mixture fed, as above described, upon the table, and allowed to spread out in the form of a thin sheet, the separation will not only take 125 place in the manner set forth but will be more pronounced. This results apparently from the fact that the rolling action of the larger particles are practically unaffected by the presence of the sheet of water on the table, while the smaller parti- 130

cles are submerged to a greater or less extent therein hindering or preventing any tendency to roll. The final result is an increase in the difference in the final velocities assumed by the varying sized particles with a consequent sharp separation into grades or classes.

The preferred contour of the upper surface of the table has been illustrated in which the travel of the material during its initial movement from the center thereof is in a downwardly curved path under the combined action of centrifugal force and gravity, and as it approaches the edge of the table is in a path curved upwardly over which it moves under the action of centrifugal force. The exact form shown is merely illustrative and may be varied to meet varying conditions of operation necessitated by changes in the material handled and its relative characteristics, but is so designed as to cause a positive rolling action of the material until it actually leaves the edge of the table. It is obvious that the exact form of the table depends also upon the speed at which the table is rotated, and that for the same form of table a comparatively wide range of control may be secured by suitably regulating its speed of rotation to change the centrifugal force tending to move material being treated.

While the device is adapted to effect a separation according to size of particles of granular material generally, the form illustrated is primarily intended and designed to effect a separation of the larger particles of gangue from the smaller particles of ore in a mixture of ores and gangue, and is particularly useful in segregating the gangue and ore particles after a preliminary classification has been effected to obtain a mixture containing gangue and ore particles which will be suspended in equilibrium by the same vertically upwardly flowing stream of water. A classification to procure such a mixture may be effected by any method or device, such as by feeding an ore containing gangue, substantially different in specific gravity, to devices such as disclosed in my previously filed applications, Serial No. 245,296, filed July 17, 1918, and Serial No. 272,327, filed January 21, 1919, details of which, however, are not necessary to an understanding of the present invention. By such devices a mixture of gangue and ore particles is secured in which the size of the gangue particles vary within certain limits and in which the ore particles also vary within certain limits, but all of which will be suspended in equilibrium by the same vertically flowing stream of water. As an example of such a graded or classified mixture, one containing silica

particles ranging from .25 to .1 and hematite particles ranging from .1 to .04 inch in diameter might be given. If the material of the example just given mixed with water is fed upon the rotating table, the silica particles because of their greater size will be ejected from the table at a decidedly greater velocity than the hematite particles which are of smaller size. Consequently, if the velocity of the table is properly regulated substantially all the silica particles will fall into the outermost compartment 6 and if the other compartments are of proper width substantially all the ore particles will drop into the inner compartment 4. Due to the fact that the smallest silica particles are of substantially the same size as the largest hematite particles, a certain number of silica and hematite particles because of their corresponding size will attain substantially the same velocity. These particles are caught by the intermediate compartment 5 and can be subsequently treated in any of the well known ways to effect a separation due to the difference in specific gravities of the two materials. Applicant's separator therefore possesses particular utility in the concentration of ores of the character named.

As above stated, and with the material taken as an example, the particles which fall into the intermediate chamber 5 are partly hematite and partly silica, all particles however being of substantially the same size. The particles of silica are therefore considerably lighter than the particles of hematite. If a blast of air of suitable intensity is forced upwardly through the chamber 5, the lighter particles of silica will be deflected upwardly without appreciably affecting the path of travel of the heavier particles of hematite. By properly regulating this upward blast, it is obvious that a very large number of the silica particles can be made to pass over into the outer compartment 6 reducing those falling into the intermediate compartment to a minimum, thereby effecting a decidedly cleaner and sharper separation. In Figs. 2 and 3 is illustrated a modified form of device utilizing the upwardly flowing air blast in the intermediate compartment.

In this modified form, an annular chamber 40 surrounds the lower reduced extremity of compartment 5 to which air under pressure is supplied through the pipe 41 having the interposed control valve 42. The chamber 40 is placed into communication with the interior of the compartment by a series of equally spaced apertures 43 extending through the wall of the compartment. In order to prevent the escape of air downwardly through the outlet 8, the same is provided with a water seal by directing

said outlet below the surface of water contained within a vat, as indicated at 44.

From the above description, the mode of operation of this form is obvious. The 5 valve 42 is opened to an extent to admit a sufficient quantity of air to cause an upward blast through the compartment 5 which will deflect the lighter silica particles causing them to travel over into the 10 outer compartment while retaining the heavier hematite particles within the intermediate compartment, otherwise operating in identically the same manner as the form previously described.

15 It is thus seen that the invention provides a device for separating granular materials composed of various sized particles, which is simple in construction, easy to operate, economical to manufacture, void 20 of all screens or shaking tables, and while adapted for general use is particularly useful in the concentration of ores or for similar purposes.

I claim:

25 1. An apparatus for grading granular material according to the size of the particles composing the same, comprising a laterally extending distributing disc or table having its entire upper plain surface 30 exposed and operative to retard sliding movement of said particles and to induce rolling action thereof, means for rotating the disc, and means for separately collecting the different sized particles discharged 35 therefrom.

2. An apparatus for grading granular material according to the size of the particles composing the same, comprising a laterally extending distributing disk or table 40 having its entire upper plain surface freely exposed and provided with a covering hindering the free sliding action but inducing rolling action of the particles, means for rotating the disk, and means for separately collecting the different sized particles 45 discharged therefrom.

3. An apparatus for grading granular material according to the size of the particles composing the same, comprising a distributing disk having its upper face unobstructed and freely exposed throughout its entire extent, means on said disk for enhancing the rolling action of the particles, means for rotating the disk, and means for 50 separately collecting the different sized particles discharged therefrom.

4. An apparatus for grading granular material according to the size of the particles composing the same, comprising a distributing disk, the upper freely exposed plain surface of which is unobstructed throughout its entire extent and slopes gradually downwardly from its central portion to a point intermediate its center and peripheral edge and thence upwardly to the 55

said edge whereby to increase the rolling action of the particles, means for rotating the disk, and means for separately collecting the different sized particles discharged therefrom.

5. An apparatus for grading granular material according to the size of the particles composing the same, comprising a distributing disk, the upper surface of which slopes gradually downwardly from its central portion to a point intermediate its center and peripheral edge and thence upwardly to the said edge whereby to increase the rolling action of the particles, the said peripheral edge being rounded, means for 70 rotating the disk, and means for separately collecting the different sized particles discharged therefrom.

6. An apparatus for grading granular material according to the size of the particles composing the same, comprising a distributing disk having its upper face unobstructed and freely exposed throughout its entire extent, a covering on the said disk for enhancing the rolling action of the particles, means for rotating the disk, and means for separately collecting the different sized particles 85 discharged therefrom.

7. An apparatus for grading granular material according to the size of the particles composing the same, comprising a distributing disk the upper surface of which slopes gradually downwardly from its central portion to a point intermediate its center and outer edge and thence upwardly in 90 an unbroken curve to the said edge, and a covering on said disk whereby to increase the rolling action of the particles, means for rotating the disk, and means for separately collecting the different sized particles 95 discharged therefrom.

8. An apparatus for grading granular material according to the size of the particles composing the same, comprising a distributing disk having its upper face unobstructed and freely exposed throughout its entire extent, a rubber covering on said disk for enhancing the rolling action of the particles, means for rotating the disk, and a plurality of concentrically arranged compartments spaced from the disk for separately collecting the particles of varying size 110 discharged therefrom.

9. An apparatus for grading granular material according to the size of the particles composing the same, comprising a distributing disk having its upper face unobstructed and freely exposed through its entire extent, the upper surface of which gradually slopes downwardly from its central portion to a point intermediate its center and peripheral edge and thence upwardly in an unbroken curve to the said edge, and a rubber covering on said disk whereby 115 to increase the rolling action of the parti- 120

cles, means for rotating the disk, and a plurality of concentrically arranged compartments spaced from the disk for separately collecting the particles of varying size discharged therefrom.

10. An apparatus for grading granular material according to the size of the particles composing the same, comprising a distributing disc having a plain upper surface unobstructed and freely exposed throughout its entire extent and operative to retard sliding movement of the said particles and to induce rolling action thereof, means for feeding the material upon the disc in the form of a thin sheet, means for rotating the disc, and a plurality of concentrically arranged annular compartments spaced at different distances from the periphery of the disc for separately collecting the particles of varying size discharged therefrom.

11. An apparatus for grading granular material according to the size of the particles composing the same, comprising a distributing disk having a plain upper surface unobstructed and freely exposed throughout its entire extent, means for feeding the material on the disk in the form of a thin sheet, the upper surface of the disk sloping downwardly from its central portion to a point intermediate its center and peripheral edge and thence upwardly in an unbroken curve to the said edge whereby to increase the rolling action of the particles, means for rotating the disk, and a plurality of concentrically arranged annular compartments spaced at different distances from the periphery of the disk for separately collecting the particles of varying size discharged therefrom.

12. An apparatus for grading granular material, according to the size of the particles composing the same, comprising a distributing disk having its upper surface unobstructed and freely exposed throughout its entire extent for enhancing the rolling action of the particles deposited on the disk, means for rotating the disk, a plurality of concentrically arranged compartments spaced from the disk for separately collecting the particles of varying size discharged from the disk, and means for directing a blast of air upwardly through an intermediate

compartment for upwardly deflecting the lighter particles passing therethrough.

13. An apparatus for grading granular material, according to the size of the particles composing the same, comprising a distributing disk having its upper surface unobstructed and freely exposed throughout its entire extent, a covering thereon offering high frictional resistance to sliding movement of the particles deposited thereon whereby to induce rolling action thereof, means for rotating the disk, a plurality of concentric annular compartments spaced from the disk, and means for directing a regulated blast upwardly through an intermediate compartment for deflecting the lighter particles passing therethrough.

14. Apparatus for grading granular material according to the size of the particles composing the same, comprising a distributing disk having its upper surface unobstructed and freely exposed throughout its entire extent and so shaped as to induce a rolling action to the particles, means for rotating the disk, a plurality of concentrically arranged compartments spaced from the disk, and means for directing a regulated blast upwardly through an intermediate compartment for deflecting the lighter particles passing therethrough.

15. Apparatus for grading granular material according to the size of the particles composing same, comprising a distributing disk having a plain upper surface unobstructed and freely exposed throughout its entire extent, means of feeding the material on the disk in the form of a thin sheet, the upper surface of the disk having a covering hindering the free sliding action but inducing rolling action of the particles, means for rotating the disk, and a plurality of concentrically arranged annular compartments spaced at different distances from the periphery of the disk for separately collecting the particles of varying size discharged therefrom.

In testimony whereof, I sign my name.
